COMBINATION CLAMP MOUNTING WITH
WINDOW LOCK AND ALARM

Alfred O. Vinz, Monterey Park, Calif.

Application May 20, 1939, Serial No. 274,779

4 Claims. (Cl. 116—16)

This invention relates to devices used for protecting against unauthorized opening of closures, such as windows.

One of the objects of this invention is to provide a device that will automatically brace itself against any opening movement though yielding to closing movements.

Another object is to provide a device that will sound an alarm upon being acted upon in a closing direction.

Another object is to provide a device that may be reversed for pressing or pulling actuations.

Another object is to provide a device that will maintain itself in operative position by means of a spring-actuated cam.

Another object is to provide a device of this type that may be held by a cam in inoperative position.

Other objects will appear from the following description as well as from the appended claims and the accompanying drawing, in which—

Fig. 1 is a side elevation of a device designed to operate according to this invention as applied to windows.

Fig. 2 is a fragmentary top plan view of the alarm-bell partly broken away to show inside parts cooperating with parts of the window-lock.

Fig. 3 is a fragmentary sectional view of parts of the window-lock as seen on line 3—3 of Fig. 2.

Fig. 4 is a cross section through the yielding sliding members of the window-lock without any other parts as seen on line 4—4 of Fig. 2.

Fig. 5 is a cross section on line 5—5 of Fig. 3 disregarding any other but the sliding parts.

Fig. 6 is a top plan view of the spring for the sliding parts.

Fig. 7 is a fragmentary schematical view of the position in which the hinge parts may be set for inoperative position.

Fig. 8 is a fragmentary, somewhat schematical illustration of the cam parts and their operations.

It is very desirable, to have windows open, not only during the day, but—also during the night against risks of burglars.

Some people prefer vertically shiftable windows partly opened at the top as well as near the bottom, requiring safety means eventually for two sashes. Setting a window so that the upper sash is partly down and the lower sash is partly up is supposed to give a better ventilation and circulation of air, the lower opening to bring in fresh air, while the upper opening is to bring air from the room to escape through this opening.

The present invention is designed and constructed so that both sashes may be controlled

at the same time by one and the same device, with an assurance that an alarm will be sounded additionally to a normal locking of the sashes against attempts of opening.

5 The bell-part of this device may be of a form to be had on the open market and of a general outline as indicated at 11 in Figs. 1 and 2. Such a type of bell is commonly provided with a bell-hammer attached to some sort of arm 12, controlled by some sort of escapement 13, as indicated in Fig. 2 under the broken-away bell-top. Such a bell may be wound for operation, to be held inoperative by merely preventing the escapement and bell-hammer from operating, as by a stop such as indicated at 14 in Figs. 2, 3, and 5.

In the present case, this stop 14 is made as a part of the yielding bell-controlling slide-part 15 of the brace 16, the stop 14 being made to move for a limited extent in a slot 17 of the brace, the stop extending upwardly into the bell that is attached to the top of the brace.

The stop 14 is normally held pressed against the bell-mechanism automatically by a spring 18 that is inserted between the slide-part 15 and the brace 16.

In order to provide for a suitable space in which the spring may operate properly, the edges 19 of the slide-part 15 are bent as indicated in Figs. 4 and 5, the bent edges forming the spacing guiding means of the slide-part 15 within the structure of the brace. The edges of the brace are also bent, or provided with lugs 20, extending over the slide-part so as to slidably hold the slide-part within the brace for movements limited by the slot 17 with respect to the stop 14.

Such movements could easily be made controllable in both opposite directions by the slot; however, inasmuch as the bracing may have to be rather strong, the whole brace-structure is designed so that the inner end 21 of the slide-member 15 can abut against the hinge-lugs of the brace, as at 22 in Fig. 3.

In other words, though the slide-part 15 makes the brace yielding, the brace is nevertheless suitably rigid when compressed beyond the yielding point. In such rigid condition, the brace may be expected to firmly act against any contrary movements of any parts against which this bracing effect is used.

In Fig. 1, for instance, the bell-supporting brace is in position braced against a portion 23 of an upper sash of a window; while the brace is supported by a clamp-mounting 24, which is clamped to the upper portion 25 of the lower sash of the same window, the clamp-mounting having

a hook-portion 26 to engage over one side of the sash while a set-screw 27 engages over the opposite side, thereby firmly holding the clamp-mounting to the sash.

The brace, however, is hingedly connected to the clamp-mounting 24 at 28, and the whole brace with the supported bell may be swung to the position indicated at 16a with respect to the clamp-mounting indicated at 24a in Fig. 7. In this inoperative position it will be held by a certain cam arrangement.

In Fig. 8, the brace-portion 16b is for this purpose shown with one plain knuckle 29 and one cam-knuckle 30; and the clamp-mounting-portion 24b is shown with 31 that is plain at one end, 15 or edge 31a and a cam-end, or edge 31b.

The cam-knuckle 30 is designed to co-operate with the cam-end 31b, the cam-knuckle 30 of the brace-portion 16b having one deeper notch 30a and a shallower notch 30b. One side-edge of the deeper notch 30a and one side edge of the cam-end 31b is suitably slanting to act as a returning means for limited movements of the brace with respect to the clamp-mounting while in bracing position so that any attempt of lifting the brace through the split between the two window-sashes will be counteracted by this returning cam-action.

The owner of the house, particularly, any person at the inside of the house, however, may get 30 the brace beyond this returning cam-action until the cam-end 31b comes to rest in the shallower notch 30b, which is equivalent to the position indicated at 16a in Fig. 7.

A plain compression spring 32 on the pintle 33 35 is inserted between the plain knuckle 29 and the plain edge 31a so as to keep the cams under the tension of this spring.

From the above it should be clear that, with the brace and sashes in the positions shown in Fig. 1, any movement of either of the sashes is 40 limited to such an immaterial extent as to make any unwarranted or unauthorized attempt towards opening the window practically impossible.

While the slide-part 15 has mainly been described as working against pressure, which is the most desirable when applied to the type of windows referred to, it should be understood that the slide-part may just as easily act against pulling, it merely requiring a slightly different mounting of the bell on the brace so that the bell-hammer and escapement comes to be located along the opposite side 34, in which case a releasing of the escapement would be in the direction of the arrow 36 instead of in the direction of the arrow 35 in which it happens to operate on the side on which the operating mechanism have been illustrated, it merely necessitating a changing of the stop 14 to the opposite side of the slide-part 15, a very insignificant mere mechanical expedient that any mechanic can produce without further showing.

Having thus described my invention, I claim—

1. In an alarm of the class described, a bell, a 65 bracing-arm made in slidably interengaging sections for longitudinal yielding, one of the sections constituting the bell-support, the other section constituting the bell-controlling member, the bell-support having hinge knuckles at the rearmost edge forming at the same time a stopping means for the yielding movements of the bell-controlling member so as to make both sections a firm non-yielding brace, the bell-support having a slot, the bell-controlling member having a lug 70 extending through the slot in the bell support at 75

a point for controlling the bell-mechanism for stopping and releasing the bell mechanism by means of the yielding actions between the two sections of the bracing-arm, and a clamp-mounting with means by which it may be clamped to the upper edge of the lower sash of a window and having hinging means for connection with the hinge knuckles of the bell-support so as to bring the free edge of the bell-controlling member into bracing engagement with the upper sash of the window.

2. In an alarm of the class described, a bell, a bracing-arm made in slidably interengaging sections for longitudinal yielding, one of the sections constituting the bell-support, the other section constituting the bell-controlling member, the bell-support having hinging means at the rear-most edge transversely to the longitudinal yielding and forming at the same time a stopping means for the yielding movements of the bell-controlling member so as to make both sections a firm non-yielding brace in compressed condition, the bell-support having a slot, the bell-controlling member having a lug extending through the slot in the bell support for controlling the bell, means between the two sections for holding them in expanded position with the lug in the slot limiting the expanding movement, and a clamp-mounting with means by which it may be clamped to the upper edge of the lower sash of a window and having hinging means for connection with the hinging means on the bell-support so as to bring the free end of the bell-controlling member into bracing engagement with the upper sash of the window.

3. In an alarm of the class described, a bell, a bracing-arm made in slidably interengaging sections for longitudinal yielding, one of the sections constituting the bell-support, the other section constituting the bell-controlling member, the bell-support having hinging means at the rearmost edge transversely to the longitudinal yielding and forming at the same time a stopping means for the yielding movements of the bell-controlling member so as to make both sections a firm non-yielding brace in compressed condition, the bell-support having a slot, the bell-controlling member having a lug extending through the slot in the bell support for controlling the bell, means between the two sections for yieldingly holding them in expanded position with the lug in the slot limiting the expanding movement of the combined bracing-arm, the lug forming the stop for the bell when in such position within the slot while the arm is in expanded position, and a clamping mounting with means by which it may be clamped to the upper edge of the lower sash of a window and having hinging means for connection with the hinging means on the bell-support so as to bring the free end of the bell-controlling member into bracing position with regard to the upper sash of the window.

4. In an alarm of the class described, a bell, a bracing-arm made in slidably interengaged sections for longitudinal yielding, one of the sections constituting the bell-support, the other section constituting the bell-controlling member, the bell-support having hinging means at the rearmost edge transversely to the longitudinal yielding and forming at the same time a stop-means for the rearmost edge of the bell-controlling member in its yielding movements so as to make both sections a firm non-yielding bracing-arm in compressed condition, the bell-support having a slot, the bell-controlling member having a lug extending

through the slot in the bell support for controlling the bell, means between the two sections for yieldingly holding them in expanded position with the lug in the slot limiting the expanding movements of the combined bracing-arm, the lug forming the stop for the bell when in such position within the slot while the arm is in expanded position, a clamp-mounting with means by which it may be clamped to the upper edge of the lower sash of a window and having hinging means for connection 10

with the hinging means on the bell-support so as to bring the free end of the bell-controlling member into bracing position with regard to the upper sash of the window, and controlling means for yieldingly holding the bracing-arm in bracing position and including means for setting the bracing-arm with the bell in inoperative position away from the upper sash while still on the lower sash.

ALFRED O. VINZ.
